UNITED STATES PATENT OFFICE.

WILLIAM EMMET ENFIELD, OF VICTOR, COLORADO.

FOLDING STOVE.

No. 865,579.

Specification of Letters Patent.

Patented Sept. 10, 1907.

Application filed November 15, 1906. Serial No. 343,611.

To all whom it may concern:

Be it known that I, WILLIAM EMMET ENFIELD, a citizen of the United States, residing at Victor, in the county of Teller and State of Colorado, have invented 5 certain new and useful Improvements in Folding Stoves; and I do declare the following to be a full, clear, and exact description of the invention, such as will enable others skilled in the art to which it appertains to make and use the same.

10 This invention relates to improvements in folding stoves, of the class usually employed by campers, prospectors, and others moving from place to place, and has for its object to improve the construction and increase the efficiency and utility of devices of this 15 character.

With these and other objects in view, the invention consists in certain novel features of construction, as hereafter shown and described, and as specified in the claims.

20 In the accompanying drawings forming a part of this specification and in which corresponding parts are denoted by like designating characters, is illustrated the preferred form of the embodiment of the invention capable of carrying the same into practical 25 operation.

In the drawings thus employed, Figure 1 is a perspective view of the device in operative position, Fig. 2 is a perspective view showing the body of the stove in folded condition; Fig. 3 is a similar view showing 30 the oven in folded condition; Fig. 4 is a perspective view of the flue supporting member; Fig. 5 is a perspective view of the removable end wall of the oven; Fig. 6 is a perspective view of the pins for holding 35 said wall in place; Fig. 7 is a perspective view showing the sections of flue disconnected; Fig. 8 is a view of the lids; Fig. 9 is a perspective view of the base members; Fig. 10 is a perspective view of the base in inverted position; Fig. 11 is a reverse plan view showing 40 the body of the stove in unfolded position; Fig. 12 is a top plan view of the flue support or socket; Fig. 13 is a vertical sectional view taken centrally and longitudinally through the stove showing the same in 45 operative position; Fig. 14 is a perspective view of the oven; Fig. 15 is an end view of the preferred form of flue; Fig. 16 is a side view of a modified form of flue; Fig. 17 is an end view of the same.

The improved device is constructed entirely from sheet metal of any suitable strength, and consists of a body portion formed of an oblong top 10, sides 11-12, 50 hingedly connected respectively to the top at 13-14, and ends 15-16 hingedly connected to the top respectively at 17-18.

The sides and ends are adapted to fold against the top and also to interfold with each other, as illustrated 55 in Fig. 2, and the end 16 is adapted to swing outwardly, and form a fuel door and closure for the oven, as here-

after explained. The body portion of the device when in unfolded or operative position is supported on a suitable base, the latter being constructed with a central opening 19 and with a vertical flange 21 at the 60 outer edges. The base is also provided with an internal flange 22 spaced from the outer flange for a short distance and of less height than the outer flange.

The bottom portion of the base is preferably formed of spaced side members 23-24 and spaced end members 25-26, crossing each other and riveted together at their ends, the interval between the bottom members forming the opening 19 above referred to.

The outer edges of the bottom members of the base are turned upwardly, then downwardly and then 70 folded inwardly and again folded upwardly as shown in Figs. 9 and 13, the folded portion forming two flanges 21-22.

The whole bottom portion of the base together with the spaced flanges is composed of the pieces 23, 24, 75 25 and 26, a very strong, durable and inexpensive structure being thus provided. The swinging end member 16 is formed with an outwardly extending shoulder 27 adapted to bear over the outer face of the flange 21 at the adjacent end of the base, the end 16 80 thus forming a movable closure to the interior of the body, and constituting both the fuel door and the closure to the oven, as hereafter explained.

The end member 16 is provided with one or more draft apertures 28, each draft aperture provided preferably with a swinging closure 29, whereby the draft will be controlled, as will be obvious.

The end portions of the outer flange 21 are provided with lateral pins, one of which is shown at 39', and the end member 16 is provided with an aperture 30 to bear 90 over one of the pins, and the end member 15 provided with a hook indicated at 31 for engaging the other pin, by which means the body portion is coupled to the base portion when in operative position as illustrated in Fig. 13.

The top portion 10 is provided with a flue aperture 32 and with pot holes 33, the latter provided with suitable covers, one of which is represented at 34. Attached to the top 10 at opposite sides of the flue aperture 32 are spaced guide members 35-36, to support a socket device upon which the smoke flue is supported. This socket device consists of a base 37 having a vertical flange 38 and lateral flanges 39-40 at the sides, the latter adapted to bear beneath the guides 35-36 and thus support the socket member in position over the flue aperture.

The flange 38 is designed to support a flue of novel construction, preferably in square form, and to couple the ordinary round flue and section of stove pipe to be supported upon the socket a circular flange 41 is attached to the base 37 and extends upwardly within the outer square flange 38, as seen in Figs. 12 and 13.

The square flue section is formed of four strips in four sheet metal plates 43, 44, 45 and 46, each having lateral flanges at their edges, the side members 43-45 having plates 47-48 attached to their inner faces longitudinally, and adapted to engage the flanges of the plates 44-46, as illustrated in Fig. 15. By this simple means, the flue portion of the device may be readily separated when the device is to be transported, or quickly connected into operative shape and supported over the 10 square flange 38 when the stove is to be used.

In Figs. 16 and 17, a modified structure of the sectional flue is shown constructed of four plates 49, 50, 51, and 52 with the edges folded into U-shape and adapted to be interlocked when in operative position, as shown.

15 Attached to the top 10 and having portions depending therefrom are catches 53, 54, 55 and 56, the catches 53-54 adapted to receive the bent ends of a wire loop 58 and the catches 55-56 adapted to receive the bent end of a wire loop 57, the loops adapted to be folded against 20 the inner face of the top 10 when not in use, and designed to support the oven portion of the device when in their depending position.

The oven portion of the device consists of a top plate 59, bottom plate 60 and side plates 61-62 hingedly 25 connected at their adjacent edges as shown at 63, so that the top and bottom and sides may be unfolded or set up into oblong form, as shown in Fig. 14.

When in open position, one end of the oven is provided with a closure 64 having flanges 65 for bearing 30 over the bottom, top and sides of the oven when in open position. When thus disposed, the closure 64 is detachably connected to the top of the oven by removable pins or tie-rods 66. The oven when in open position and provided with its end closure, is adapted 35 to be supported on the hangers 57-58 with its open end against the swinging end 16 of the body, the swinging end thus forming a closure to the oven, as will be obvious.

It will thus be noted that a simply constructed and 40 inexpensive foldable stove is produced, which may be

readily set up when required or folded into small space when not required, or when it is to be stored or transported.

Stoves of the character herein shown and described are generally employed out of doors or upon the ground 45 under temporary shelter, such as booths, tents or the like, and when the stove is to be removed, the accumulated ashes will fall through the opening 19 and remain upon the ground, the opening 19 thus obviating the necessity for removing ashes through the door 16. 50 The opening 19 also lightens the structure, and decreases the expense of construction.

The parts may be of any required size, and of any suitable material.

Having thus described the invention, what is 55 claimed is:—

1. A collapsible stove comprising a base having inner and outer marginal flanges, spaced apart, a body comprising a top and foldable side and end walls hinged thereto, the sides and one of the end walls being adapted to seat at 60 their lower edges in the space between the flanges when the device is set up for use and the other end wall being formed to seat at its lower edge over the adjacent end flange of the base, and means for securing said end wall in closed position. 65

2. In a collapsible stove, a body comprising a top and foldable side and end walls pivotally connected therewith, a pair of spaced hanger bails terminally pivoted to said top and depending therefrom upon the interior of the stove and an oven supported on said bails, the latter being 70 adapted when not in use to fold against the inner face of the top. 70

3. A collapsible stove comprising a top and side and end walls pivotally connected therewith, one of said end walls constituting a fuel door, a pair of bails pivoted to 75 and depending from the under side of the top, and an oven supported by said bails, said oven having an open end disposed toward and adapted to be closed by the fuel door.

In testimony whereof I have hereunto set my hand 80 in presence of two subscribing witnesses.

WILLIAM EMMET ENFIELD.
